WINDOW BRACKET.

William Walter King, Portage La Prairie,
Manitoba, CanadaApplication May 19, 1937, Serial No. 143,555
In Canada September 14, 1936

9 Claims. (Cl. 292—262)

My invention relates to an improvement in fasteners of a type designed for use for fastening storm windows, doors, and other relatively hinged members.

- 5 It is an object of my invention to provide a fastener for a window, door, or the like, wherein the relatively hinged members can be spaced any distance from a maximum open position to entirely closed position and be firmly held. My
10 fastener is so designed that the relatively hinged parts can be spaced apart and held rigidly in any adjusted position. The construction is such that the two portions are held together as firmly in one position as in another.
- 15 It is a feature of my invention to utilize a steel tape or the like, having a curved cross-section as a connecting means between a bracket on one member and a second bracket on a relatively swingable member. This tape permits the relative swinging of the members when more than a predetermined pressure is exerted in either direction. The tape is sufficiently rigid to resist normal pressures tending to swing one member relative to the other.
- 20 25 It is an added feature of my invention to provide a fastening means which may be quickly and readily removed from one or either of the brackets on either of the relatively swingable members. Thus the fastener is suitable for use on storm windows and the like, which are removed each fall and spring.

Another feature of my invention is to provide a locking means on one of the brackets on one member engageable with the bracket on the other member to lock the two members closed when desired. This means acts automatically upon the closing of the members together.

40 These and other objects and novel features of my invention will be more clearly and fully set forth in the following specification and claims.

In the drawing:

Figure 1 illustrates a fragmentary portion of a window frame and a storm window sash between which my fastener extends.

45 Figure 2 is a plan view of one of the brackets of my device, illustrating the construction thereof.

Figure 3 is a side elevation view of the bracket shown in Figure 2.

50 Figure 4 is an end view of the bracket illustrated in Figures 2 and 3.

Figure 5 discloses the window frame and storm window sash in relative closed position and discloses a locking means which may be used in connection therewith.

Figure 6 discloses a slightly modified form of the bracket illustrated in Figures 2, 3 and 4.

Figure 7 is a perspective fragmentary view of the fastener in detached position.

5 My fastener A is shown in the drawing as connecting a window frame B and a storm window sash C. A bracket 10 is mounted on the frame B by screws 11 or by other suitable means. The bracket 10 comprises 15 a strip of metal or the like, bent to provide oppositely disposed flanges 12 and a central flange 13 formed by folding the strip back upon itself. The flange 13 extends at substantially right angles to the plane of the oppositely disposed flanges 12. 20 This flange 13 is preferably only a portion of the width of the flanges 12 to provide a wide bearing for the oppositely disposed flanges 12.

The fastener A extends between a window frame B and a storm window sash C. A bracket 10 is mounted on the frame B by screws 11 or by other suitable means. The bracket 10 comprises 15 a strip of metal or the like, bent to provide oppositely disposed flanges 12 and a central flange 13 formed by folding the strip back upon itself. The flange 13 extends at substantially right angles to the plane of the oppositely disposed flanges 12. 20 This flange 13 is preferably only a portion of the width of the flanges 12 to provide a wide bearing for the oppositely disposed flanges 12.

To the flange 13 I secure one end of a tape 14 by means of the T-head rivet 15 or by other suitable means. An elongated slot 16 in the flange 13 extends at right angles to the T-head of the rivet. In the drawing, the slot 16 is shown extending longitudinally with respect to the tape 14, while the T-head of the rivet 15 is in transverse relation to the tape. The shape of the rivet and slot is illustrated in Figure 7.

25 The tape 14 is formed of steel or other suitable material and is arcuate in cross-section to prevent buckling of the tape. This tape 14 may be 30 of any suitable width or may be doubled to provide two thicknesses of tape if necessary or desirable.

Upon the sash, C, I mount a bracket 17. This bracket 17 is formed with a base plate 18 having 40 side flanges 19 on either side thereof and having a flange 20 projecting at right angles thereto. Brace members 22 extend from the flange 20 to the base 18 to reinforce the flange 20. The bracket 17 is secured to the sash C by screws 23 45 or the like.

A pair of oppositely disposed notches 24 are formed in the flange 20. Within these notches 24 fit the doubled extremities 25 of a spring clip 26 which holds the tape 14 to the bracket 17. 50 The clip 26 is formed of resilient material and may be sprung into and out of place. This clip 26 is provided with a pair of oppositely disposed arms 27, the ends 28 of which extend into apertures 29 in ears 30 integral with the side flanges 55

19 of the base 18. The arms 27 extend to form the extremities 25 and are doubled over for a short distance at the extremity and then connect by the cross member 32.

5 The tape 14 extends between the flange 20 and the cross member 32 of the clip 26. The tape then bends at right angles to itself and extends between the side flanges 27 and beneath the arms 19 to terminate at 33. A terminal member in the form of a half round wire clip 34 secured in oppositely disposed notches in the end 33 of the tape prevents the movement of this end of the tape 14 past the extremities 28 of the clip 26. The bending of the tape 14 at right angles and the passing of the tape between the clip 26 and the bracket 17 provides a friction which is sufficient to hold the sash C in any adjusted position from movement by wind, rain, or snow.

20 In order to lock the window sash C to the frame B, I provide a locking means illustrated in Figure 5 of the drawing. This means comprises a latch 35 pivoted on a pintle 36 extending through the parallel braces 22 on the clip 17 and engageable over the flange 13 of the bracket 10. The hook end 37 of the latch 35 engages this flange 13 and prevents the swinging of the sash C away from the frame B until the latch is released. It may be seen that this latch 35 will close automatically and the hook end 37 will rest upon the top surface of the tape 14, will slide over the rounded head of the bolt 15 and over the edge of the flange 13.

35 In order to prevent the extremity 33 of the tape 14 from depending too far below the bracket 17, it is possible for me to provide a bracket 36 similar to the bracket 17 but having integral therewith a cylinder 37 within which the tape will roll upon itself and be contained when the 40 sash C is drawn close to the frame B. The extremity 33 of the tape 14 may in this way be at all times concealed and may cause the tape 14 to curl up in a spiral roll within the cylinder 37.

45 The manner in which the tape 14 may be released from the bracket 10 may be easily seen. The end of the tape 14 must be held at right angles to its normal position, the head of the rivet 15 inserted through the slot 16, and the tape then turned into proper position to be readily removed from the bracket 10 when desired. The tape 14 may also be released from the bracket 17. This is accomplished by flexing inwardly the arms 27 of the spring clip 26 to release the 50 ends 28 thereof from the openings 27 in the ears 30. When the ends 28 are released the spring clip 26 as a whole may be slidably disengaged from the notches 24 in the flange 20. Thus the tape may be quickly removed from the bracket 17 for disengaging the tape 14 from this bracket, or for replacing the tape 14.

60 In accordance with the patent statutes I have described the principles of construction of my fastener and while I have endeavored to set forth the best embodiments thereof, I desire to have it understood that this is only illustrative of a means of carrying out my invention and that obvious changes may be made within the scope of the following claims without departing from the spirit of my invention.

70 I claim:

1. A fastener for a pair of relatively pivotal members including a bracket secured to one of

said members, a steel tape connected to said bracket, a bracket on the other of said pivotal members, and means on said last named bracket frictionally engaging said tape, said means sharply changing the direction of said tape and overlying a substantial length thereof adjacent said change of direction.

5 2. A fastener for relatively movable members comprising a bracket secured to one of said members, a tape anchored to said bracket, and means on the other of said members for frictionally engaging said tape, said means acting to sharply change the direction of said tape.

10 3. A fastener for a pair of relatively movable members comprising a tape capable of withstanding considerable compression without bending, means for anchoring said tape to one of said movable members, and means on the other of said members for frictionally engaging the other end of said tape and causing a sharp 20 bend therein.

15 4. A fastener for relatively movable members including a bracket on one of said members, a tape anchored to said bracket, a bracket on the other of said members, and spring clip means for detachably and frictionally connecting said tape to said last named bracket, said spring 25 resiliently engaging said tape.

20 5. A fastener for relatively movable members including a bracket on one of said members, a metallic tape arcuate in cross-section connected to said bracket, a bracket on the other of said members, and spring clip means securing said tape to said bracket in a manner to change the direction of said tape, said spring clip acting to 30 bend said tape and flatten the same at said bend.

25 6. A fastener for a pair of relatively movable members including a bracket on one of said members, a tape arcuate in cross-section connected to said bracket, a bracket on the other of said members, and means on said last named bracket for changing the direction of said tape to flatten the tape arcuation at the bend to 40 provide spring tension between said last named bracket and said tape.

35 7. A fastener for relatively movable members including a bracket on one of said members, a tape secured to said bracket, a bracket on the other of said members frictionally engaging said tape, said last named bracket sharply bending 50 said tape, and latch means on said last named bracket engageable with the first named bracket to lock said brackets and said members together.

45 8. A fastener for relatively movable members including a flexible tape, means for removably connecting said tape to one of said members, a bracket frictionally engaging said tape, said last named bracket being mounted on the other of said members, and substantially cylindrical hollow guide means on said last named bracket having a slot therein through which said tape extends into said hollow guide means for guiding said tape into a spiral roll.

55 9. A fastener for relatively movable members including a bracket on one of said members, a second bracket on the other of said members, and means anchored to one of said brackets frictionally and slidably engageable with the other of said brackets at a sharp bend in said tape to hold said members at any required distance apart.

70 WILLIAM WALTER KING.
